UNITED STATES PATENT OFFICE

2,615,374

SLICE ASSEMBLY FOR PAPERMAKING MACHINES

Bernard A. Malkin, Lachine, Quebec, Canada, assignor to Dominion Engineering Works Limited, Lachine, Quebec, Canada

Application October 4, 1948, Serial No. 52,642

19 Claims. (Cl. 92—44)

1

This invention relates to a slice assembly for paper making machines and the object is to provide a generally improved assembly in which the slice plate is adjustably mounted in a novel manner so that it has a wide range of adjustment both with respect to its elevation and with respect to its position along the length of the fourdrinier wire or other sheet forming element.

According to this invention the slice plate is secured to the lower portion of a slice plate carrier arranged between and adjustably supported by the pond plates of the slice. The upper portion of the slice plate carrier is supported from the pond plates by supporting means adjustable to raise and lower the slice plate carrier and designed to provide a pivotal axis about which the slice plate carrier is swingable to shift the slice plate to different positions of adjustment along the length of the fourdrinier wire or other sheet forming element. The lower portion of the slice plate carrier is also supported from the pond plates by supporting means adjustable to swing the slice plate carrier about said axis.

Several preferred embodiments of the invention are shown in the accompanying drawings, in which—

Fig. 1 is a side elevation, partly broken away, of a slice assembly embodying the invention.

Fig. 2 is a front elevation, partly broken away, of the assembly shown in Fig. 1.

Fig. 3 is a vertical transverse sectional view of the assembly shown in Figs. 1 and 2.

Fig. 4 is a front elevational view of a modified form of assembly embodying the invention.

Fig. 5 is a side elevational view of the modified assembly shown in Fig. 4.

Fig. 6 is a vertical sectional view taken substantially along the section line 6—6 of Fig. 4.

Fig. 7 is a vertical sectional view taken substantially along the section line 7—7 of Fig. 4.

Fig. 8 is a detail view of one of the spring loaded studs forming part of the assembly shown in the preceding figures.

The slice assembly shown in Figs. 1 to 3 inclusive, includes an apron 5 over which the stock flows onto the fourdrinier wire 6 at the breast roll 7. This apron is arranged between vertical pond plates 8 so that its delivery edge 9 constitutes the lower lip of the slice. The upper lip of the slice is formed by the lower edge 10 of a flexible slice plate 11 which is mounted so that it may be raised and lowered and may also be swung about a horizontal axis to different positions of adjustment along the length of the fourdrinier wire.

2

Slice plate 11 is secured to the lower portion of a slice plate carrier 12 which preferably comprises a hollow frame structure adjustably supported by and between the pond plates 8. A pair of aligned shafts 13 are rotatably supported in the upper portion of slice plate carrier 12 with their inner ends coupled to shafts 14 of a worm gear reduction unit 15 which is driven by a shaft 16 equipped with a hand wheel 17. The outer ends of shafts 13 are coupled to pinion shafts 18 journalled in gear casings 19 secured to the sides of carrier 12 adjacent the upper front corners of said carrier. A relatively small pinion 20 is fixed to each pinion shaft 18 and meshes with a larger pinion 21 carried by a shaft 22 also journalled in gear casing 19. The outer portion of each pinion shaft 22 is formed to provide an eccentric stub shaft 23 journalled in a bearing 24 carried by a bracket 25 secured to the front edge of one of the pond plates 8. The eccentric stub shafts 23 provide a horizontal pivotal axis about which the carrier 12 and slice plate 11 may be swung to shift the slice plate to different positions of adjustment along the length of the fourdrinier wire 6. These eccentric stub shafts 23 also serve to raise and lower the carrier 12 and slice plate 11 with reference to the fourdrinier wire 6 when said eccentrics are rotated in their bearings 24 by operation of the hand wheel 17.

A pair of aligned shafts 27 are rotatably supported in the lower portion of carrier 12 with their inner ends coupled to shafts 28 of a worm gear reduction unit 29 which is operated by a shaft 30 equipped with a hand wheel 31. The outer end of each shaft 27 is coupled to a pinion shaft 32 journalled in a gear casing 33 secured to one side of carrier 12. Pinion shaft 32 carries a small pinion 34 meshing with a relatively large pinion 35 fixed to a shaft 36 journalled in gear casing 33. Shaft 36 carries a small pinion 37 meshing with a larger pinion 38 carried by a pinion shaft 39 also journalled in gear casing 33. Shaft 39 also carries an eccentric stub shaft 40 fitted in a bearing 41 provided at one end of a tie rod 42 having its other end pivotally connected to the outer side of one of the pond plates 8 by trunnion 43 and tie rod bearing 43a. As here shown each tie rod 42 includes a turn buckle arrangement 43b which enables the tie rod to be shortened or lengthened to vary the distance between the pivotal axis 40 and the pivotal axis 43.

When it is desired to shift slice plate 11 to different positions of adjustment along the length

of the fourdrinier wire 6 this is accomplished by operating hand wheel 31 to rotate stub shafts 40 in their tie rod bearings 41. Further adjustment of the slice plate 11 to different positions along the length of the fourdrinier wire 6 may be obtained by varying the effective length of the tie rods 42 through the agency of the turn buckle or other length adjusting means provided for this purpose. When the carrier 12 and slice plate 11 are being raised and lowered by rotation of the upper eccentric stub shafts 23 in their bearings 24, the tie rods 42 function as supporting links for the lower portion of the carrier.

As clearly shown in Fig. 3, the carrier 12 comprises a casing having a top wall 53, front and rear walls 54 and 55, side walls 56, a V-shaped bottom wall 57 and internal wall stiffening plates 58, 59 and 60. The reduction gear units 15 and 29 are supported, respectively, on the stiffening plates 60 and 58.

In order to ensure an efficient water seal between the carrier 12 and the pond plates 8, the sides of the carrier are provided with spring loaded studs 45 (Figs. 2 and 8) extending outwardly through slots 46 in the pond plates 8 and equipped with nuts 47. Each stud 45 is encircled by a loading spring 47a confined between a washer 47b bearing against the pond plate 8 and a second washer 47c bearing against nut 47. The washers 47b and 47c are provided with opposing bosses 47d and 47e. The boss 47e is provided with stop projections 47f which fit in slots 47g in the boss 47b and are engageable with the bottom walls of said slots to limit the extent to which spring 47a can be compressed by tightening the nut 47.

An important advantage of the slice assembly shown in Figs. 1 to 3 inclusive is that the driving mechanisms for the upper and lower eccentric stub shafts 23 and 40 are protected by the carrier 12 and by the reduction gear casings carried by said carrier. This arrangement also provides a very compact assembly of the carrier 12 and its adjustable supporting means.

It is preferred that the apron assembly 5 be adjustable so that it may be shifted horizontally to different positions of adjustment relative to the vertical axis of the breast roll 7. As shown in Fig. 3, the apron assembly 5 including liner plate 49 is slotted as indicated at 50 to accommodate a stud 51 carried by a stationary casting 52 which is attached to and forms part of a stationary head box (not shown).

Figs. 4 to 7 inclusive illustrate a modified slice assembly in which the mechanism for adjusting carrier 12 and slice plate 11 are located outside said carrier. In this case the upper portion of carrier 12 is provided, at each side with a trunnion 70 journalled in a bearing block 71 arranged to slide in a vertical guide 72 machined in the adjacent pond plate 8. Each bearing block 71 is raised and lowered by a vertically adjustable rod 73 having its lower end pivotally secured to said bearing block as indicated at 74. A threaded worm pinion 75 is screwed onto the upper portion of each rod 73 and is supported on a suitable thrust bearing 76 arranged within the gear casing 77.

Each worm pinion 75 is driven by a worm wheel 78 fixed to a shaft 79 journalled in casing 77. The outer ends of shafts 79 are provided with hand wheels 80 and the inner ends of said shafts are connected together by a coupling shaft 81.

The trunnions 70 and bearing blocks 71 provide a horizontal axis about which carrier 12 and slice plate 11 may be swung to shift the slice

plate to different positions of adjustment along the length of the fourdrinier wire.

The mechanism shown in Figs. 4 to 7 inclusive for swinging carrier 12 about its pivotal axis comprises a pair of tie rods 84 each having one end pivoted to a bracket 85 fastened to the front of carrier 12. The other end of each tie rod 84 is provided with a bearing 86 fitted on an eccentric shaft extension 87 of a shaft 88 journalled in a bearing 89 carried by one of the pond plates 8. The eccentric shaft extensions 87 located at opposite sides of the slice are connected together by a coupling shaft 90. One of the shafts 87 extends into a gear casing 91 and is provided with a worm wheel 92 which is driven by a worm 93 fixed to the lower portion of a vertical shaft 94 equipped at its upper end with a hand wheel 95. The upper portion of shaft 94 is journalled in a suitable bearing 96 (Fig. 4) carried by one of the pond plates 8. By rotating hand wheel 95 the eccentricities 87 may be rotated in their tie rod bearings 86 to shift the tie rods in a direction to swing carrier 12 and slice plate 11 about the pivotal axis afforded by the trunnions 70.

The tie rods 84 shown in Figs. 4 to 7 inclusive, include turn buckles 96a by means of which the effective length of the tie rods may be varied as and for the purpose previously described in connection with the tie rods shown in Figs. 1 to 3 inclusive.

In slices of the type to which this invention relates it is customary to provide means for flexing the lower edge of the slice plate 11 and a conventional adjusting means for this purpose is indicated at 98 in the present drawings. It is also customary in slices of this type to provide a flow distributor behind the slice plate 11 and in Fig. 6 I have shown a conventional distributing roll 99 which is preferably mounted in adjustable bearings 100 (Fig. 5) so that said roll may be adjusted forwardly and rearwardly to compensate for forward and rearward shifting of the slice plate 11 in the longitudinal direction of the fourdrinier wire. The distributing roll 99 may be driven by any suitable form of driving means such as that indicated at 101 in Fig. 4.

I claim:

1. In a pond and slice assembly of the character described, a pair of laterally spaced, vertically disposed pond plates, a slice plate carrier arranged between said pond plates, a slice plate secured to the lower portion of said carrier, means supporting the upper portion of said carrier from the upper portion of the pond plates, said supporting means being adjustable to raise and lower said carrier and including carrier supporting pivots affording a horizontal axis about which the carrier is swingable to shift the slice plate to different positions of adjustment and additional supporting means supporting the lower portion of the slice plate carrier from the lower portion of the pond plates, said additional means comprising adjustable link members each having one end pivotally secured to one side of the lower portion of the slice plate carrier and the other end pivotally secured to the lower portion of one of said pond plates, said link members being adjustable to swing said slice plate carrier to different positions of adjustment about said horizontal axis.

2. In a pond and slice assembly of the character described, a sheet forming element, an apron over which the stock is delivered to said forming element, vertically extending pond plates disposed at opposite sides of said apron,

a slice plate carrier arranged between said pond plates, a slice plate secured to the lower portion of said carrier and cooperating with the delivery edge of the apron to form the mouth of the slice, means supporting the upper portion of the carrier from the upper portion of said pond plates, said supporting means affording a horizontal axis about which the carrier is swingable to shift the slice plate to different positions of adjustment along the sheet forming element and being adjustable to raise and lower said carrier and slice plate and additional supporting means connected between the lower portion of the carrier and the pond plates and adjustable to swing the carrier about said axis, 10 said additional supporting means comprising adjustable link members each having one end pivotally secured to one side of the lower portion of the slice plate carrier and the other end pivotally secured to the lower portion of one of said pond plates.

3. A pond and slice assembly as set forth in claim 2, in which the means supporting the upper portion of the slice plate carrier from the upper portion of the pond plates includes rotatable eccentrics journaled in stationary bearings carried by the pond plates and supporting said carrier.

4. A pond and slice assembly as set forth in claim 2, in which the means supporting the upper portion of the carrier from the upper portion of the pond plates includes pivots forming part of said carrier and journaled in bearings supported by the pond plates.

5. A pond and slice assembly as set forth in claim 2, in which the means supporting the upper portion of the carrier from the upper portion of the pond plates includes pivots forming part of the carrier and fitted in vertically adjustable bearings carried by the pond plates.

6. A pond and slice assembly as set forth in claim 2, in which the adjustable supporting means supporting the upper portion of the carrier from the upper portion of the pond plates comprises stationary bearings secured to said pond plates, rotatable eccentrics rotatably journaled in said carrier and in said bearings and means for rotating said eccentrics in said bearings to raise and lower said carrier, said eccentrics and bearings affording a horizontal axis about which the carrier is swingable to shift the slice plate to different positions of adjustment along the sheet forming element.

7. A pond and slice assembly as set forth in claim 6, including a hand operated gear reduction unit supported by said carrier, shafts driven by said unit and gearing through which each of said eccentrics is driven from one of said shafts.

8. A pond and slice assembly as set forth in claim 2, in which the additional supporting means supporting the lower portion of said carrier from the lower pond plates comprises link members pivotally connected to the carrier and to the pond plates, said link members being adjustable in length.

9. A pond and slice assembly as set forth in claim 2, in which the additional supporting means supporting the lower portion of the carrier from the pond plates comprises a pair of links, means pivotally connecting one end of each link member to the carrier and means pivotally connecting the remaining ends of the link members to the pond plates.

10. A pond and slice assembly as set forth in

claim 9, in which the means pivotally connecting each link member to said carrier comprises a bearing forming part of the link member and an eccentric rotatably supported in the carrier and rotatably fitted in said bearing whereby rotation of said eccentrics in said bearings is effective to swing the carrier about said axis.

11. A pond and slice assembly according to claim 9, in which the means pivotally connecting each link member to one of the pond plates comprises a bearing forming part of the link member and an eccentric rotatably journaled in the pond plate and rotatably fitted in said bearings so that rotation of said eccentric is effective to swing said carrier about said axis.

12. A pond and slice assembly as set forth in claim 2, in which the carrier and slice plate extend across the forming elements from one pond plate to the other and in which means are provided for holding the sides of the carrier in sealing engagement with the inner side surfaces of the pond plates.

13. In a pond and slice assembly of the character described, a pair of laterally spaced, vertically elongated pond plates, a slice plate carrier arranged between said pond plates, pivot shafts carried by the upper portion of the slice plate carrier and journaled in bearings carried by the upper portion of the pond plates to provide a pivotal axis about which the slice plate carrier is swingable to different positions of adjustment and means for swinging said slice plate carrier to said different positions of adjustment comprising adjustable link members each having one end pivotally secured to one side of the lower portion of the slice plate carrier and the other end pivotally secured to the lower portion of one of said pond plates.

14. In a pond and slice assembly of the character described, a pair of laterally spaced, vertically disposed pond plates, a slice plate carrier arranged between said pond plates, bearings carried by the upper portions of said pond plates, pivot shafts carried by the upper portion of the slice plate carrier and fitted in said bearings to provide a pivotal axis about which the slice plate carrier is swingable to different positions of adjustment and means for swinging said slice plate carrier to said different positions of adjustment comprising link members pivotally connected at one end to the lower portions of said pond plates and at the other end to the lower portion of the slice plate carrier, the pivotal connections at corresponding ends of said links constituting part of eccentric mechanisms by means of which axial movement is imparted to the links to swing the slice plate carrier about said pivotal axis.

15. In a pond and slice assembly of the character described, a pair of vertically disposed pond plates arranged in spaced parallel relation, a slice plate carrier arranged between said pond plates, a slice plate secured to the lower portion of said carrier, pivot shafts carried by the sides of the slice plate carrier adjacent the upper end of said carrier, slide bearings in which said pivot shafts are rotatably fitted, said slide bearings working in guides carried by the upper portions of the pond plates, means for raising and lowering said guides, and slice plate carrier adjusting mechanism connected between the lower portions of the slice plate carrier and the pond plates and operable to swing the slice plate carrier to various positions of adjustment about the pivotal axis afforded by the pivot shafts and

75

slide bearings, said slice plate carrier adjusting mechanism comprising a pair of link members having corresponding ends pivotally secured to the slice plate carrier and eccentrics rotatably carried by the lower portions of the pond plates and operatively connected to the remaining ends of said links, whereby the links are operated in response to rotation of said eccentrics to swing the slice plate carrier about the pivotal axis afforded by said pivot shafts.

16. In a pond and slice assembly of the character described, a pair of vertically disposed pond plates arranged in spaced parallel relation to each other, a slice plate carrier arranged between said pond plates, a slice plate secured to the lower portion of said carrier, bearing brackets carried by the upper portions of the pond plates, pivot shafts journalled in bearings carried by the upper portions of the side walls of the slice plate carrier, the outer portions of said pivot shafts projecting laterally beyond the sides of the slice plate carrier and being formed to provide eccentric stub shafts rotatably journalled in said bearing brackets to provide a horizontal axis about which the slice plate carrier is swingable to various positions of adjustment, means for rotating said stub shafts to raise or lower said pivotal axis and to effect a corresponding raising and lowering of the slice plate carrier, and slice plate carrier adjusting mechanism connected between the lower portions of the slice plate and the pond plates and operable to swing the slice plate carrier about said pivotal axis, said slice plate carrier adjusting mechanism comprising adjustable link members each having one end pivotally secured to one side of the lower portion of the slice plate carrier and the other end pivotally secured to the lower portion of one of said pond plates.

17. In a pond and slice assembly of the character described, a pair of vertically disposed pond plates arranged in spaced parallel relation to each other, a slice plate carrier arranged between said pond plates, said carrier comprising a hollow casing having top, front, rear, bottom and side walls, a slice plate secured to the lower portion of said carrier, bearing brackets secured to the upper portions of the pond plates, gear casings secured to the upper portions of the sides of said carrier, pivot shafts journalled in said gear casings with the outer ends of said shafts projecting from the gear casings and formed to provide eccentric stub shafts journalled in said bearing brackets to provide a pivotal axis about which said carrier is swingable to various positions of adjustment, additional shafts journalled in said gear casings with the inner ends of said shafts extending into the upper portion of said carrier, said additional shafts being geared to said pivot shafts to drive the latter, shaft rotating means housed in the upper portion of

5 said carrier in driving engagement with the inner ends of said additional shafts and carrier adjusting mechanism connected to the lower portion of said carrier and operable to swing the latter to various positions of adjustment about said pivotal axis, said carrier adjusting mechanism comprising adjustable link members each having one end pivotally secured to one side of the lower portion of the slice plate carrier and the other end pivotally secured to the lower portion of one of said pond plates.

10 18. A pond and slice assembly as set forth in claim 18, in which said shaft rotating means comprises a manually operable gear reduction unit housed in the upper portion of said carrier and shafts through which power is transmitted from said gear reduction unit to the said additional shafts journalled in the gear casings.

15 19. In a pond and slice assembly of the character described, a pair of vertically disposed pond plates arranged in spaced parallel relation to each other, a slice plate carrier arranged between said pond plates, a slice plate secured to the lower portion of said carrier, means pivotally supporting the upper portion of said carrier from the upper portion of the pond plates and affording a horizontal axis about which the carrier is swingable to shift the slice plate to different positions of adjustments and means 20 connected between the lower portions of the pond plates and said carrier for swinging said carrier to its different positions of adjustment about said pivotal axis, said last mentioned means comprising a pair of link members having corresponding ends thereof pivotally secured to the lower portions of the pond plates, gear casings secured to the lower portions of the sides of said carrier, shafts journalled in said gear casings, the outer portions of said shafts projecting 25 outwardly beyond said gear casings and being formed to provide eccentric stub shafts fitted in bearings carried by the remaining ends of said links and manually operable power transmitting shafts carried by said carrier and geared to said first mentioned shafts for operating the latter and the links to swing said carrier and the links about said pivotal axis.
